(57) **CLAIM**

The ornamental design for a combined trigger and bottle, as shown and described.

DESCRIPTION

FIG. 1 is a top, front and left isometric view of the combined trigger and bottle showing our new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1; and,

FIG. 6 is a top plan view of FIG. 1.

The broken lines are for the purpose of illustrating environmental structure and form no part of the claimed design. Further, the bottom view forms no part of the claimed invention.

The broken lines are included for the purpose of illustrating portions of the combined trigger and bottle that form no part of the claimed design. Further, the bottom view forms no part of the claimed invention.
